UNITED STATES PATENT OFFICE.

EDWARD SEITZ, OF PEORIA, ILLINOIS.

PRESSER-FOOT-ATTACHMENT HOLDER FOR SEWING-MACHINES.

SPECIFICATION forming part of Letters Patent No. 373,312, dated November 15, 1887.

Application filed June 9, 1887. Serial No. 240,778. (No model.)

To all whom it may concern:

Be it known that I, EDWARD SEITZ, of Peoria, in the county of Peoria and State of Illinois, have invented certain new and useful Improvements in Presser-Foot Attachments for Sewing-Machines; and I do hereby declare that the following is a full, clear, and exact description of the invention, which will enable others skilled in the art to which it appertains to make and use the same, reference being had to the accompanying drawings, and to the letters of reference marked thereon, which form part of this specification.

This invention relates to certain improvements in attachment-holders for sewing-machines; and it has for its objects to so construct the presser-foot that the various devices—such as hemmers, gatherers, braiders, and the like—employed in connection with said machines may be readily and conveniently attached to or removed from the presser-foot, as occasion may require, in changing from one character of work to another, as more fully hereinafter specified. These objects I attain by the means illustrated in the accompanying drawings, in which—

Figure 1 represents a side elevation of the presser-foot of a sewing-machine constructed according to my invention, showing a gatherer secured thereto. Fig. 2 is an enlarged vertical sectional view of the presser-foot attachment and device for securing the same, taken on the line *x x* of Fig. 1. Fig. 3 represents a longitudinal sectional view taken on the line *y y* of Fig. 2, showing the detached toe of the presser-foot in place. Fig. 4 is a vertical sectional view of the presser-foot, showing a modification of my invention. Fig. 5 is a vertical sectional view taken on the line *x x* of Fig. 4, and Fig. 6 represents a vertical sectional view showing another modification of my invention.

Referring to the drawings, the letter *A* indicates the presser-foot of a sewing-machine, which is formed with the usual socket, *a*, and set-screw *b*, by means of which it may be secured to the lower end of the presser-foot bar, as usual. The lower portion of the presser-foot is provided with a rectangular or other shaped horizontal recess, *c*, which extends from the front to the rear, and which forms a socket or seat for the shank *d* of the various attachments. The presser-foot, as illustrated

in Figs. 1, 2, and 6 of the drawings, is provided with a vertical tapering recess extending through it from side to side, which connects at its lower end with the horizontal recess before mentioned, and within which is fulcrumed a cam-lever, *B*, which works in the tapering recess and draws in the attachment and holds it in position, against one side of which bears a small leaf-spring which holds it by frictional contact when elevated. The lever is also provided with a stop, *e*, at one side, which limits its motion when it is raised. As shown in Figs. 1 and 2, the cam-lever is provided with a lug, *g*, at its edge, which engages a transverse groove, *h*, in the shank *d* of the attachment when the lever is elevated. The shank *d* is rectangular in cross-section, so as to accurately draw in and fit the horizontal recess or socket in the presser-foot, and is shouldered at *i*, the shoulder abutting against the forward edge of the presser-foot and forming a stop for the attachment to limit the extent of its insertion and adjust it accurately in place.

In the modification shown in Figs. 4 and 5 of the drawings the vertical transverse recess is omitted and in its place is formed a cylindrical recess, *D*, which crosses the horizontal recess at right angles thereto. Through said recess passes and is journaled therein a cam-shaft, *F*, which is provided with a crank-arm, *K*, at one end, by which it may be turned in its bearings. The said shaft is recessed at one side, as indicated by the letter *m*, (see Figs. 4 and 5,) so that when the crank-arm is turned down, the recess will be in line with the horizontal recess in the presser-foot, so as to permit the shank of the attachment to be inserted and withdrawn, and when turned up the solid cam portion of said shaft will be turned into the transverse recess in the shank, so as to draw in, bind, and hold the same to the presser-foot.

In the modification shown in Fig. 6 the edge of the cam-lever enters the transverse slot and binds and holds the shank and its attachment.

Having thus described my invention, what I claim, and desire to secure by Letters Patent, is—

1. The combination, with the presser-foot of a sewing-machine, having a horizontal recess extending from the front to the rear of

the same, of a sewing-machine attachment having a shank provided with a transverse tapering recess, said shank being inserted in the horizontal recess in the presser-foot, and the fastening device engaging said tapering recess to draw in, bind, and hold the shank and attachment, substantially as specified.

2. The combination, with the presser-foot having a recess extending from the front to the rear of the same, and a transverse vertical recess, of a cam-lever fulcrumed in said vertical transverse recess, and a sewing-machine attachment having a transverse slot in its shank with which said cam-lever engages, substantially as specified.

3. The combination, with the presser-foot having recesses, as described, of the cam-lever having a lug at its edge and a stop at one side, the spring bearing against said lever, and a sewing-machine attachment having a recess in its shank with which the cam-lever engages, substantially as specified.

In testimony that I claim the foregoing as my own I affix my signature in presence of two witnesses.

EDWARD SEITZ.
